UNITED STATES PATENT OFFICE

170,552

CHILD'S SHOE

Rubin Sherman, Lowell, Mass.

Application April 10, 1953, Serial No. 24,447

Term of patent 3½ years

(Cl. D7—7)

To all whom it may concern:

Be it known that I, Rubin Sherman, a citizen of the United States, residing at Lowell, Massachusetts, whose post-office address is 230 Jackson Street, Lowell, Massachusetts, have invented a new, original and ornamental Design for a Child's Shoe of which the following is a specification, reference being had to the accompanying drawing, forming a part thereof, in which:

Figures 1 and 2 show perspective views of the shoe.

I claim:

The ornamental design for a child's shoe, as shown.

RUBIN SHERMAN.
